UNITED STATES PATENT OFFICE

100,019

DESIGN FOR AN ILLUMINATING FIXTURE

Edwin F. Guth, Webster Groves, Mo.

Application March 12, 1936, Serial No. 61,603

Term of patent 3½ years

To all whom it may concern:

Be it known that I, Edwin F. Guth, a citizen of the United States and a resident of Webster Groves, St. Louis County, Missouri, have invented a new, original, and ornamental Design for Illuminating Fixtures, of which the following is a specification, reference being had to the accompanying drawing, forming part thereof, in which the figure is an elevational view of an illuminating fixture showing my new design.

I claim:

The ornamental design for an illuminating fixture, substantially as shown.

In testimony whereof, I have signed my name to this specification this 9th day of March, 1936.

EDWIN F. GUTH.
